Patented Sept. 27, 1927.

UNITED STATES PATENT OFFICE.

HELEN C. GATCHELL, OF CHICAGO, ILLINOIS.

STREET SIGN.

Application filed December 6, 1926. Serial No. 152,839.

This invention relates to street signs and the like and is particularly adapted to be used on globes of lights which are placed at street corners and carries signs giving 5 the names of the streets.

The invention is fully described in the following specification and shown in the accompanying drawings, in which:

Figure 1 is a top plan view of the device 10 secured on a lamp globe;

Fig. 2 is a side elevation of the same;

Fig. 3 is a partially enlarged section on the line 3—3 of Fig. 2;

Fig. 4 is a partially enlarged section 15 showing details of the frames on the line 4 of Fig. 2; and

Fig. 5 is a partially enlarged detail of the ends of the frame.

The embodiment illustrated comprises a 20 metal ring 10 which is adapted to overlie and be supported by a glass globe A which is carried upon a post (not shown) by means of a rim B and screws C which engage the lower flanged portion A' of the globe. An electric lamp (not shown) illuminates the globe A in a well known manner.

The ring 10 has a series of lugs 11 secured thereon at intervals, these lugs bearing 30 upon the globe A and spacing the ring from the globe so that water, snow and ice will not accumulate between the ring and the globe.

A series of frames 12 are hingedly carried 35 by the ring 10, preferably by means of lugs 13 which are pivotally secured to the lugs 11 by means of screws or pins 14. These pins are horizontally disposed so that the frame 12 is free to swing about them.

40 A spring finger 15 is secured to the lower portion of each of the frames 12, the lower end of the spring finger 15^a lying within the rim B. These spring fingers serve to hold the frames upon the globe and keep them 45 in a horizontal position. At the same time the spring fingers preferably have a leaf 15^b which bears against the lower side of the globe to provide a resilient means for taking up any looseness in the device and 50 preventing a rattle.

The frames 12 are preferably made up of strips of U-shaped material at the top and bottom and a similar piece 12^a at one end as shown in Figs. 3 and 5, while the opposite end is open and provided with bars 55 12^b so that plates of glass or the like 12^c

may be inserted through this latter end. These plates of glass may be painted or otherwise lettered to designate the street toward which this portion of the sign is turned as shown in Fig. 2.

The ends of the frames are provided with overlapping ears 12^d which have registering openings 12^e which are adapted to receive bolts 12^f. These bolts may be short as shown in Fig. 2, and they may, if desired, be long enough to extend through from top to bottom of the frames. In either case they may rigidly secure the frames together so that when placed upon the globe of a street lamp, 70 the frames assume a definite position with respect to each other as shown in Figs. 1 and 2, while the resilient fingers 15 hold the whole in a horizontal position.

Thus it will be understood that light from 75 the street lamp shining through the transparent glass portions 12^c will illuminate the sign carried thereon so that it will be clearly visible for a considerable distance from the street lamp. It will thus be seen that I 80 have invented a simple and unique sign and one which can be economically manufactured and easily applied to existing street lamps.

While I have shown and described but a 85 single embodiment of this invention, it is to be understood that it is capable of many modifications. Changes therefore in the construction and arrangement may be made 90 which do not depart from the spirit and scope of the invention as disclosed in the appended claims.

I claim:

1. A street sign comprising, in combination, a transparent globe, a support therefor, 95 a ring adapted to fit around the upper part of said globe, inwardly projecting lugs spaced at intervals on said ring and adapted to bear upon said globe, sign carrying frames hingedly mounted on said ring, and means 100 for steadyng said frames.

2. A street sign comprising, in combination, a transparent globe, a support therefor, a ring adapted to fit around the upper part of said globe, inwardly projecting lugs 105 spaced at intervals on said ring and adapted to bear upon said globe, sign carrying frames hingedly mounted on said ring, and means for securing said frames to said support.

3. A street sign comprising, in combination, a transparent globe, a support therefor, a ring adapted to fit around the upper part 110

2
of said globe, inwardly projecting lugs spaced at intervals on said ring and adapted to bear upon said globe, sign carrying frames hingedly mounted on said ring, and resilient fingers extending from said frames and engaging said support.

4. A street sign comprising, in combination, a transparent globe, a support therefor, a ring adapted to fit around the upper part 10 of said globe, inwardly projecting lugs spaced at intervals on said ring and adapted to bear upon said globe, sign carrying frames hingedly mounted on said ring, means for securing adjacent ends of said frames together, and means for holding the frames in substantially horizontal positions.

5. A street sign comprising, in combination, a transparent globe, a support therefor, a carrying member adapted to bear upon 20 said globe at a plurality of points, a plurality of sign frames pivotally carried by said

member, and means on said frames adapted to engage said support to position said frames.

6. A street sign comprising, in combination- 25, a transparent globe, a support therefor, a carrying member adapted to bear upon said globe at a plurality of points, a plurality of sign carrying frames pivotally carried by said member, and resilient fingers on said 30 frames adapted to engage said support to position said frames.

7. A street sign comprising, in combination, a transparent globe, a support therefor, a carrying member adapted to bear upon said 35 globe at a plurality of points, a plurality of sign frames pivotally carried by said member, means on said frames adapted to engage said support to position said frames, and means for securing together the adjacent 40 ends of said frames.

HELEN C. GATCHELL.
